UNITED STATES PATENT OFFICE.

JOHN H. D. PETERSEN, OF CHICAGO, ILLINOIS, ASSIGNOR TO LINK-BELT COMPANY, OF CHICAGO, ILLINOIS, A CORPORATION OF ILLINOIS.

COAL-HANDLING APPARATUS.

1,375,105.

Specification of Letters Patent. Patented Apr. 19, 1921.

Application filed August 12, 1918. Serial No. 249,468.

To all whom it may concern:

Be it known that I, JOHN H. D. PETERSEN, a citizen of the United States, residing at Chicago, in the county of Cook and State 5 of Illinois, have invented a certain new and useful Improvement in Coal-Handling Apparatus, of which the following is a specification.

My invention relates to apparatus for 10 handling and storing coal or the like, particularly at the mine head or the sizing plant, or receiving and distribution point, and for storing it or a portion of it adjacent thereto and returning it to the distribution 15 point when desired, and my object, generally speaking, is to effect this result by the least possible amount of permanent machinery or apparatus.

The operation of my invention is further 20 described in a process application copending, Number 249,467.

There are several minor objects and portions of the apparatus which have particular functions hereafter to be explained.

25 The invention is illustrated more or less diagrammatically in the accompanying drawings wherein

Figure 1 is a diagrammatic plan view of a plant illustrative of my invention;

30 Fig. 2 is a side elevation of a portion of the apparatus;

Fig. 3 is a detailed side elevation looking in the direction of arrow 3 of Fig. 2;

Fig. 4 is a detailed cross-section of a portion 35 of the apparatus.

Like parts are indicated by the same letter in all the figures.

A is a diagrammatic illustration of the 40 distribution plant. A¹ is a conveyer preferably a belt conveyer leading therefrom. A² is a hollow tower over which the conveyer A¹

travels; A³ a head pulley over which the conveyer runs; A⁴ a chute of any desired length into which the conveyer discharges;

45 A⁵ is a movable crane having an arm A⁶ from the outer end of which is operatively suspended the conveyer bucket A⁷ adapted to operate on the pile of material A⁸ and A⁹ is the railroad track on which the crane A⁵ 50 may travel. All these parts are diagrammatically illustrated.

B is a short, approximately horizontally disposed conveyer near the bottom of the hollow tower A² preferably in a side recess 55 associated therewith and underneath the

opening at B¹ which is preferably provided with inclosing walls set near the angle of repose of the material to be dealt with. B² B² are the buckets of a conveyer which is adapted to operate vertically in the hollow 60 tower and B³ is the chute capable of being raised and lowered and adapted to discharge in its lower position onto the conveyer belt A¹. B⁴ is a dotted line indicating the surface of the pile of coal over the opening B¹, 65 and B⁵ is a dotted line to indicate the position of the surface of the coal or other material when the conveyer B has been operated so as to draw off all the material lying above the opening B¹. 70

It will be obvious as we proceed with the discussion of the use and operation of these several parts that they may be greatly altered and changed and some omitted and substitutes be provided without departing 75 from the spirit of my invention. In short, my drawings are only diagrammatic drawings, although working apparatus could be made following very closely the structure here illustrated. 80

The use and operation of my invention are as follows:—

At a coal distribution plant there is an unequal accumulation of material due to seasonal demands. Thus, there may be in 85 the winter a very considerable accumulation of coal not suitable for the winter trade but suitable for the summer trade and this coal must either be treated so as to be fit for the season in which it is produced or be stored. 90

An object of this invention is to provide convenient means whereby that storage may be effected by a given apparatus which can then when desired be reversed in its operation to return such storage coal or materials 95 to the distribution center.

For example the summer coal accumulated in the winter may be carried by the belt conveyer A¹ over and discharge into the pile A⁸. Here it is picked up by the crane 100 and deposited in the area about the crane and along the tracks and this operation is continued from time to time, such unseasonable coal being steadily stored at a convenient point adjacent to the distribution point. 105 When the time has arrived for the use of such coal, it should be returned to the distribution point for whatever treatment may there be required and then for distribution in the usual way. This is accomplished in 110

the following manner. The conveyer belt B is set in operation, the vertical conveyer within the pockets B² is set into operation and the chute B³ is put into the position shown in dotted lines in Fig. 2 and the travel of the belt A¹ is reversed. The action is to withdraw through the aperture B⁴ from the coal pile at the foot of the hollow tower the coal which is then taken up by the buckets of the vertical conveyer, carried to and discharged along the reversed belt conveyer and by it carried back to the distribution house.

Meantime, the crane is operated to pick the material from the pile about the tracks A⁹ and drop it over the aperture B⁴. This operation is facilitated by the fact that the coal has been drawn away from the center of the pile A⁸ as indicated by the dotted line in Fig. 4 so as to leave a large upwardly opening funnel whose walls are composed of coal. In the top of this funnel the crane can easily drop its load and the material passes down through the aperture B⁴ onto the belt B.

In this way the coal is compelled to form its own unloading chute or funnel and to dispense with any hopper with inclined bottom walls. Of course this opening could be placed at a considerable distance from the hollow tower if desired so as to give a more uniform or symmetrical coal pile and funnel opening but what is here illustrated is sufficient for the purpose. The arrangement of the belt conveyer, vertical conveyer and associated parts is such that the material is first carried to the bottom of the tower and then by reversing the belt and operating the vertical conveyer, can be carried back over the same route to the distribution point.

I claim:—

1. An apparatus for handling material comprising a conveyer adapted to carry material in either direction between a distribution point and an intermediate point, a second conveyer adapted to carry such material in either direction between the intermediate point and a storage point and a third conveyer adapted to carry the material from the intermediate point to the adjacent end of the first conveyer.

2. An apparatus for handling material comprising a substantially horizontally disposed belt conveyer adapted to carry material in either direction between the distribution point and an intermediate point, a second conveyer adapted to carry such material in either direction between the intermediate point and a storage point, and a third conveyer adapted to carry the material from the intermediate point to the adjacent end of the first conveyer.

3. An apparatus for handling material comprising a conveyer adapted to carry ma-

terial in either direction between a distribution point and an intermediate point, a second crane-and-bucket conveyer adapted to carry such material in either direction between the intermediate point and the storage point and a third conveyer adapted to carry the material from the intermediate point to the adjacent end of the first mentioned conveyer.

4. An apparatus for handling material comprising a conveyer adapted to carry material in either direction between a distribution point and an intermediate point, a second conveyer adapted to carry such material in either direction between the intermediate point and a storage point and a third substantially vertically acting conveyer adapted to carry the material from the intermediate point to the adjacent end of the first conveyer.

5. An apparatus for handling material comprising a conveyer adapted to carry material in either direction between a distribution point and an intermediate point, a second conveyer adapted to carry such material in either direction between the intermediate point and a storage point and a third substantially vertically acting conveyer adapted to carry the material from the intermediate point to the adjacent end of the first conveyer such third conveyer contained in a hollow tower.

6. An apparatus for handling material comprising a conveyer adapted to carry material in either direction between a distribution point and an intermediate point, a second conveyer adapted to carry such material in either direction between the intermediate point and a storage point and a third substantially vertically acting conveyer adapted to carry the material from the intermediate point to the adjacent end of the first conveyer such third conveyer contained in a hollow tower, the first mentioned conveyer discharging near the top of said hollow tower and the third mentioned conveyer receiving near the bottom of such tower.

7. An apparatus for handling material intermittently in opposite directions between two points comprising a reversible conveyer extending between the two points and a reversible intermittently operating conveyer at one end of such reversible conveyer together with an intermittently operated elevator adapted to connect said reversible and said intermittently operating conveyer.

8. An apparatus for handling material intermittently in opposite directions between two points comprising a conveyer extending between two points and adapted to deposit the material at one end with a vertically acting intermittently moving conveyer adapted to pick the material up and deposit it on such end of said first conveyer and a conveyer adapted intermittently to receive

material from the first conveyer and deliver it to the second.

9. A coal handling apparatus comprising a horizontal conveyer, a hollow tower supporting the discharge end thereof above the ground level, means for supplying coal to the conveyer for operating the conveyer, means for piling the coal discharged from the end of the conveyer on the ground about 5 the hollow tower, means for picking up the coal so deposited and depositing it in a storage pile, means for returning the coal from the storage pile and depositing it on the ground about the hollow tower, means 10 for raising the coal so deposited to the top of the hollow tower and discharging it upon the horizontal conveyer and means for moving the conveyer in the opposite direction to carry away such coal.
- 15 10. A coal handling apparatus, comprising a hollow tower, an elevator therein, a conveyer having one end adjacent the hollow tower, means for discharging coal from said conveyer and depositing it on the ground about the hollow tower and means 20 for discharging coal from the elevator onto such conveyer, means for changing the direction of operation of the conveyer and means for causing the flow of coal from 25 the pile around the base of the hollow tower to the elevator.
- 30 11. A coal handling apparatus comprising a hollow tower, an elevator therein, a conveyer communicating with the top thereof, means for piling coal about the base of the hollow tower on the ground, means 35 interposed between the base of the pile and the elevator whereby the coal so piled may be fed to the elevator and means for operating the conveyer either to withdraw coal fed to it by the elevator or to discharge coal 40 across the hollow tower onto the ground adjacent the base thereof.

- 45 12. A coal handling apparatus comprising a hollow tower, an elevator therein, a conveyer communicating with the top thereof, means for piling coal about the base of the hollow tower on the ground, means interposed between the base of the pile and the 50 elevator whereby the coal so piled may be fed to the elevator and means for operating

the conveyer either to withdraw coal fed to it by the elevator or to discharge coal across the hollow tower onto the ground adjacent the base thereof, means for selectively removing the coal from the pile at the base of the hollow tower and placing it in a storage pile or moving coal from the storage pile and piling it up about the base of the hollow tower. 55

60 13. A coal handling apparatus comprising a coal elevator, a conveyer adapted to receive coal therefrom, means for piling the coal up about the base of the elevator, a chute whereby coal is withdrawn from the base of the coal pile and discharged into the conveyer.

65 14. A coal handling apparatus comprising a coal elevator, a conveyer adapted to receive coal therefrom, means for piling the coal up about the base of the elevator, a chute whereby coal is withdrawn from the base of the coal pile and discharged into the conveyer the chute being arranged so that the coal as it is piled about the base 70 of the elevator forms a cone hopper and guides the coal added to the pile downwardly into the gravity chute.

75 15. A coal handling apparatus comprising a hollow tower, material elevating means therein, means for piling material about the tower, means for passing such material directly to the elevating means, a reversible conveyer adapted either to feed material about the tower or to convey away 80 the material lifted by the elevator therein.

85 16. An apparatus for handling material intermittently in opposite directions between two points comprising a reversible conveyer extending between the two points and a reversible intermittently operating conveyer at one end of such reversible conveyer, together with an intermittently operating conveying means adapted to connect said two conveyers. 90

95 In testimony whereof, I affix my signature in the presence of two witnesses this 9th day of August 1918.
